UNITED STATES PATENT OFFICE

ISADORE O. WITTE, OF LOS ANGELES, CALIFORNIA

DESIGN FOR A FONT OF TYPE

Application filed January 23, 1931. Serial No. 38,429. Term of patent 7 years.

To all whom it may concern:

Be it known that I, ISADORE O. WITTE, a citizen of the United States, residing at 4190 Third Avenue, Los Angeles, in the county of Los Angeles and State of California, have invented a new, original, and ornamental Design for Font of Type, of which the following is a specification, reference being had to the accompanying drawing, forming part thereof.

The figure is a plan view of a font of type showing my new design.

I claim:

The ornamental design for a font of type as shown.

ISADORE O. WITTE.
